BY *Henry Hes.*
ATTORNEYS

UNITED STATES PATENT OFFICE.

HARRY JULIUS SCHOTTELKORB, OF PASCO, WASHINGTON.

NECKTIE.

1,326,292.

Specification of Letters Patent. Patented Dec. 30, 1919.

Application filed July 11, 1919. Serial No. 310,043.

To all whom it may concern:

Be it known that I, HARRY JULIUS SCHOTTELKORB, a citizen of the United States, and a resident of Pasco, in the county of Franklin and State of Washington, have invented certain new and useful Improvements in Neckties, of which the following is a specification.

My invention relates to neckties and more particularly a necktie adapted to be used as a bow tie.

An important object of my invention is to provide a necktie of this class which may be adjusted by the wearer to present the appearance of a bow tie without requiring any especial skill on his part or any assistance of another.

Another object is to provide a necktie of neat and attractive appearance, simple and durable in construction and easy and inexpensive to manufacture.

Other objects and advantages reside in certain novel features of the construction, arrangement and combination of parts and will become apparent as the description proceeds, reference being had to the accompanying drawings forming part of this specification and in which:

Figure 1 is a perspective view of the tie, the tying ends being folded and the central band being positioned as in use,

Fig. 2 is a perspective view of the tying ends and adjacent parts,

Fig. 3 is a detail perspective view of the central band.

Referring to the drawings, it will be seen that the numeral 5 designates a neck band having one end looped as at 6 and associated with a sliding buckle 7 whereby the neck band may be lengthened or shortened to suit the size of the collar worn by the wearer.

A link 8 is positioned on the looped portion of the neck band prior to the assembling of the same with the sliding buckle and after the assembly the link is normally positioned in the bight 6' of the loop.

A tying end 9 is secured to the outer portion of the link 8 preferably by stitching or the like 9', as shown in Fig. 2. It is to be noted that the link is of such size as to provide a space between the tying end 8 and the bight 6' for a purpose to be hereinafter described.

The other tying end 10 is secured to the

other end of the neck band 5 by suitable stitching or the like 10'. The neck band 5 may be of any suitable material but is preferably of a cheaper and less highly finished material than the tying ends which of course 60 may be plain colors or any of the usual ornaments.

The central band 11 is shown in detail in Fig. 3 and co-operates with the tying ends 9 and 10, as shown in Fig. 1 in a manner 65 to be hereinafter more fully described. The material forming the central band is preferably elastic and is of such color, texture and design as to correspond with the like qualities of the tying ends and to accurately 70 simulate the appearance of the central loop of a bow knot or tie.

In fixing the tie on the collar the wearer first adjusts the length of the neck band to suit the size by means of the sliding buckle 7. The central band 10 is then slipped over one of the tying ends on to the neck band. The tying end 9 is then folded over on itself and the tying end 10 is passed through the space provided in the link 8 80 and then passed between the folds of the tying end 9. The folds of the tying ends are held in this position while the elastic central band 10 is moved to the central portion of the fold as shown in Fig. 1. The 85 elastic gripping action of the central band causes the folds to be maintained in proper position and also causes the adjacent portions of the folds to be tucked thereby more closely simulating the appearance of the 90 bow knot or tie. It is obvious that the folds of the tying ends are so arranged with respect to each other as previously described and as shown in Fig. 1 that their looped ends are properly spaced and formed to 95 simulate a bow tie and that no skill is required to arrange the parts in proper position.

I claim:

1. A necktie comprising a neck band having one end looped and associated with a sliding buckle to vary its length, a link engaged in the bight of said looped end, a tying end directly secured to the outer portion of said link and adapted to be folded over on itself, a tying end directly secured to the other end of said neck band and adapted to be passed through said link and between the folds of said first mentioned tying end and an elastic band adapted to 110

be engaged over the center of the folds of said tying ends to simulate with said folds the appearance of a bow tie.

2. A necktie comprising a neck band, a link associated with one end of the neck band, a tying end directly secured to the outer portion of said link, said tying end being adapted to be folded over on itself, a tying end directly secured to the other end 10 of said neck band and adapted to be passed through said link and between the folds of said first mentioned tying end, and an elastic band adapted to be engaged over the center of the folds of said tying ends to simulate

with said folds the appearance of the bow 15 tie.

3. A necktie comprising a neck band, a tying end directly secured to one end of said neck band and adapted to be folded over on itself, said neck band being provided adjacent said tying end with an opening, a second tying end directly secured to the other end of said neck band and adapted to be passed through said opening and between the folds of said first mentioned tying 25 end and means for maintaining said tying ends in position to simulate a bow tie.

HARRY JULIUS SCHOTTELKORB.
